UNITED STATES PATENT OFFICE.

EDGAR H. MUMFORD, OF PHILADELPHIA, PENNSYLVANIA.

JOLT-RAMMING APPARATUS.

1,017,685.

Specification of Letters Patent. Patented Feb. 20, 1912.

Application filed September 29, 1909. Serial No. 520,096.

To all whom it may concern:

Be it known that I, EDGAR H. MUMFORD, a citizen of the United States, residing at Philadelphia, in the county of Philadelphia and State of Pennsylvania, have invented certain new and useful Improvements in Jolt-Ramming Apparatus, of which the following is a specification.

My invention has relation in general to sand molding, and in particular to apparatus for jolt ramming the sand in sand molds. It has for its primary objects the provision of an improved apparatus of jolt ramming sand molds, wherein the impact or jolt is developed by arresting the movement of sufficient mass to lift the mold bodily; and the provision of an improved apparatus for jolt ramming sand molds in which the impact or jolt is delivered by a moving element which gives but a single shock during its cycle of movement, and wherein there is no appreciable jarring imparted to the floors supporting the mold apparatus and the jolting apparatus. These together with such other objects as may hereinafter appear, I attain by means of a device illustrated in the accompanying drawing, wherein

The figure is a partial section and end elevation of an apparatus embodying my invention.

In general my method consists in ramming the sand molds by means of a blow developed by arresting the movement of a mass which is projected against the mold apparatus. It is preferable to develop the blow from a direction below upward, the moving mass striking a superimposed mold apparatus, and, when put in motion, having sufficient inertia to move a substantial distance upward carrying the mold apparatus along with it. The return of the mass and the mold apparatus is cushioned so that there is no jar subsequent to the initial jolt or blow.

In carrying out my method I provide an operating ram or plunger 7 mounted for reciprocation in the upper end of a U shaped chamber or cylinder 8 and having a head 9 which is adapted to strike a superimposed platform or table 10, on which the mold 11 is placed. The cylinder 8 is partially filled with a liquid 12, preferably water, and has an inlet 13 for the admission of fluid pressure controlled by suitable

valve mechanism. A baffle plate 14 is provided adjacent the inlet to secure a uniform distribution of the fluid pressure at initial admission, and to retain the water in the cylinder on release of pressure. A packing 15 of the usual character is provided at the upper end of the cylinder to prevent the escape of the water and air, and a supporting stool 16 is provided within the cylinder to form a seat for the ram when the device is idle. Supporting brackets 17 are employed in securing the cylinder in proper position.

The operation of the device is as follows:—On admission of pressure through the inlet 13, the water is depressed in that portion of the chamber or cylinder 8 adjacent the inlet and raised in the opposing portion, thereby projecting the ram 7 upward, the head 9 of the ram striking against the platform 10. The ram and its head are of great weight and their inertia is proportionately great, so that the blow developed by the impact on the platform and mold apparatus is severe. The inertia carries the ram together with the platform and the mold apparatus a substantial distance upward the object being to prevent repeated and irregular jars. On the downward movement the ram is cushioned by the air in the cylinder, the amount of which, together with the proper exhaust and admission thereof, is controlled by valve mechanism (not shown) preferably operated by the movement of the ram at proper intervals. This cushioning permits the ram and with it the mold apparatus to return comparatively slowly, thereby eliminating shocks subsequent to the initial jolt which would undo its work. As an additional means for securing a gentle return of the mold apparatus, the posts 18 of the supporting platform may be provided with collars 19 bearing against springs 20, which will absorb any shock occasioned in the return. It is obvious that various other means may be equally well employed in cushioning the return of the mold apparatus and the ram, as for instance dash mechanism in the cylinder to retard the return of the water.

It is to be observed that the cylinder 8 has its peculiar U shape to accomplish two objects. On the downward movement of the ram any shock that might occur, due to imperfect cushioning or accident or other

cause, would be directed upwardly against the air cushion, thereby relieving the floor from strains and jars. Furthermore the air is prevented from going through the water and bearing directly against the ram 7, which would interfere with the successful operation of the device.

It is also to be noted that the shock produced by the ram striking against the plat-
10 form is away from the floor, and the return of the ram and mold apparatus being cushioned as before set forth, there is little or no jar or vibration of the supporting floor. By using an interposed liquid between the
15 ram and the actuating fluid, the advantages of both liquid and fluid pressure are secured. Other advantages will readily present themselves to those familiar with the art.

Having thus described my invention and 20 illustrated its use, what I claim as new and desire to secure by Letters Patent is the following:—

1. In combination in jolt ramming apparatus, a mold support; and means for im-
25 parting a blow to the support from beneath and for carrying the support upward with such means after the blow is struck.

2. In combination in jolt ramming apparatus, a mold support, means for imparting 30 a blow to the support from beneath and carrying the support upward with such means after the blow is struck, and then returning the support comparatively slowly to starting position whereby a reverse jolt
35 is avoided.

3. In combination in jolt ramming apparatus, a mold support, means for imparting a blow to the support from beneath and carrying the support upward with such means 40 after the blow is struck, and means for cushioning the return movement of the support.

4. In combination in jolt ramming apparatus, a mold support and a ram beneath 45 the support arranged to strike the support

and carry such support upward therewith a substantial distance.

5. In combination in jolt ramming apparatus, a mold support, a ram beneath the support arranged to strike the support and 50 carry such support upward therewith a substantial distance, and means for retarding the return movement of the support and reducing the jar incident thereto.

6. In an apparatus for jolt ramming sand 55 molds, the combination with a mold apparatus, of means for moving the mold apparatus upward with a jolt, and means for cushioning the return of said means.

7. In an apparatus for jolt ramming sand 60 molds, the combination with a mold apparatus, of a ram for moving the mold apparatus upward with a jolt, pneumatic means for operating the ram, and a body of liquid interposed between the ram and the pneu- 65 matic means.

8. In an apparatus for jolt ramming sand molds, the combination with a mold apparatus, of a ram for moving the mold apparatus upward with a jolt, a cylinder therefor with its lower portion turned laterally 70 and carrying a body of liquid, and means for supplying air pressure to the body of liquid to cause it to operate the ram.

9. In an apparatus for jolt ramming sand 75 molds, the combination with a mold apparatus, of a ram for moving the mold apparatus upward with a jolt, a cylinder therefor with its lower portion formed with an upturned bend carrying a body of liquid, and 80 means for supplying air pressure to the surface of the liquid in the upturned bend.

In testimony whereof, I have hereunto signed my name in the presence of the two subscribed witnesses.

E. H. MUMFORD.
